CONTINUOUS INDUCTIVE TRAIN CONTROL SYSTEM

Filed Nov. 30, 1925

UNITED STATES PATENT OFFICE

WADE H. REICHARD, OF ROCHESTER, NEW YORK, ASSIGNOR TO GENERAL RAILWAY SIGNAL COMPANY, OF ROCHESTER, NEW YORK

CONTINUOUS INDUCTIVE TRAIN-CONTROL SYSTEM

Application filed November 30, 1925. Serial No. 72,290.

This invention relates to automatic train control and more particularly concerns a train control system of the continuous inductive type embodying means for checking the operation of the car-carried receiving apparatus.

In an automatic train control system of the well known continuous inductive type, control currents flow in the track rails under favorable traffic conditions only, these control currents serving to transmit influences to car-carried receiving and control equipment which is adapted to initiate a restrictive control when these currents are cut off and no influences are transmitted. One modified system of continuous inductive train control contemplates the use of a so-called acknowledging means which permits a train to proceed under unfavorable traffic conditions, that is, over sections of trackway or blocks in which no control currents are flowing, without automatic restriction, provided a suitable manual acknowledging act is performed as the train enters each block in which unfavorable traffic conditions exist, the acknowledging act at the entrance to a block in which unfavorable traffic conditions exist serving to temporarily place the car-carried apparatus in an inactive condition. In such a system, the control apparatus on the vehicle is again placed in its active condition by the transmission of a momentary impulse from the trackway at a point near the entrance end of each track block, under unfavorable, as well as favorable, traffic conditions, unless the said manual acknowledging act is repeated at this point.

Since the failure of the receiving equipment while the vehicle is traversing a block in which unfavorable traffic conditions exist would prevent the transmission of the momentary impulse at the entrance to the succeeding block under unfavorable traffic conditions, and so prevent the restoration of the car-carried apparatus to its active condition, it is very essential that the car-carried receiving equipment on a system of this type shall operate properly, and that its operation, particularly while the vehicle is trav-

eling under unfavorable traffic conditions, be checked in some safe manner.

As certain portions of the trackway, such as sidings, branch lines and the like, are usually not equipped for train control operation, it is necessary to provide means for rendering the car-carried equipment inactive for train operation in these unequipped or non-train control sections. This operation in non-train control territory is usually provided for by the use of special trackway impulse transmitting means for enabling the car-carried apparatus to be rendered inactive, these means being located at the entrance to the unequipped territory, and to provide further impulse transmitting means at points where equipped sections of trackway are again entered, for placing the car-carried equipment in its active controlling condition. As in the case of train operation under unfavorable traffic conditions, it is desirable to check the proper operation of the car-carried receiving equipment while the vehicle is traveling in the unequipped trackway sections, as the failure of this receiving equipment at such points would prevent the restoration of the control apparatus to its active condition as the vehicle re-enters equipped or train control territory, thus permitting the vehicle to proceed in train control territory without the protection of automatic control.

With the above and other considerations in mind it is proposed in accordance with the present invention to provide a train control system in which the car-carried controlling apparatus may be placed in the inactive condition for vehicle travel under unfavorable traffic conditions in equipped sections of trackway and for vehicle travel in unequipped sections of trackway, and in which means are provided for checking the operation of the car-carried receiving equipment while in its inactive condition. More specifically, it is proposed to provide an automatic train control system of the continuous inductive type in which the car-carried restrictive controlling apparatus may be rendered inactive for vehicle travel in successive track blocks under unfavorable traffic condi-

tions, and for vehicle travel in unequipped trackway sections, by the cooperation of a manual act on the part of the engineer and the transmission of an influence from the trackway, and in which the proper operation of the vehicle receiving equipment is checked while the restrictive control apparatus is inactive by means of the energization of the receiving equipment from a car-carried source of energy.

Other specific objects, advantages and characteristic features of the present invention will become apparent as the description thereof progresses.

In describing the invention in detail, reference will be made to the accompanying drawing in which the trackway and car-carried apparatus of a continuous inductive train control system embodying the present invention has been shown in a diagrammatic and simplified manner.

The present invention is applicable to many forms of continuous inductive train control systems, but in order to simplify the disclosure, the invention has been shown in connection with a typical train control system of the continuous inductive three-position type. As this type of train control system is in general well known to those skilled in the art, its construction will be only briefly described.

Referring to the trackway apparatus, the track rails 1 have been shown divided into blocks and sections by the insulating joints 2, and the block I and a portion of the block H in train control territory, the excess energy section J and a portion of the block K in non-train control territory have been shown. As the various devices and circuits in the several blocks in train control territory are substantially identical, the apparatus will be described in connection with one block only, the corresponding elements in the adjacent blocks being referred to by like reference characters having distinctive exponents. For convenience, the letters B and C have been used in the drawing to designate the opposite terminals of a suitable source of direct current energy, preferably a storage battery.

Referring to the trackway apparatus, the usual track relays 3 are connected across the track rails at the entrance end of each block, these relays being of the direct current type in the embodiment shown, and being supplied with current under favorable traffic conditions from the track battery 4, connected across the track rails at the exit end of each block. Alternating train control current is supplied to the two track rails of each block in series through the transformer 5 whose secondary winding is connected across the track rails at the exit end of the block in series with the track batteries 4 as clearly shown. The application of the train control current to the track rails is controlled by the contacts of re-

lays energized in accordance with traffic conditions in advance. In the block H, this control of the train control current is effected by the track relay 3 of the block I, while in the block I the train control current is controlled through the contact fingers 8 and 9 of the line relay 10, the energization of this relay 10 being controlled in accordance with traffic conditions as hereinafter described.

Wayside signals of the color light, semaphore or other suitable type are preferably used in connection with the system of the present invention, and for the purpose of illustration, semaphore signals Z have been shown in the entrance end of each block in a conventional manner only, a showing of the operating devices and circuits for these signals being omitted, as this equipment is well known to those skilled in the art and forms no part of the present invention.

In the system shown, an acknowledging loop is used at the exit end of each block, the loop in block H, comprising the wires 11°, located adjacent the track rails for a short section of trackway and ending at the exit end of the block. Each loop is continuously supplied with alternating current of train control frequency, by means of a transformer, such as 12° for block H, connected to the transmission line 13. The primary winding of a transformer 14°, in block H, is included in series with the acknowledging loop 11° as shown. This transformer serves to supply train control current to the track rails through the contact fingers 6 and 7 of the track relay 3 and a circuit which is obvious from the drawings. This connection of the trackway acknowledging loops 11° to the source of supply of the train control current delivered to the track rails acts as a check on the energization of the acknowledging loops, a break or de-energization of the acknowledging loops causing the failure of supply of current to the track rails and so instituting danger traffic conditions.

A short insulated section of track rails, termed the excess energy section, is provided at a point along the trackway where un-equipped or non-train control territory is entered. Alternating train control current is supplied to the track rails of this section through the transformer 16 as clearly shown, the magnitude of this current being appreciably greater than that supplied to the track rails of the blocks in train control territory. In order that the train control and signaling trackway apparatus in the block I may reflect traffic conditions in advance, a track relay 17, of the alternating current type, is connected across the rails at the entrance end of the section J, and the line relay 10 controlling the train control current in the block I is energized through a front contact of this relay, and of the track relay 18 associated

with the first block K in non-train control territory.

It is apparent from the description given and the disclosure in the drawings that when a train is located in a given block, track circuit current is shunted from the track rails of that block by the wheels and axles of the train, de-energizing the track relay at the entrance end of that block and so causing the train control current to be cut off from the track rails of the first block in the rear of such occupied block.

Referring now, more particularly, to the car-carried apparatus, a railway vehicle has been conventionally represented in the block H by the wheels and axles 19, the normal direction of traffic being indicated by the arrow. This vehicle is provided with suitable inductive receiving coils 20 and 21, which may or may not be provided with laminated iron cores. The coils 20 and 21 are mounted in inductive relation to the track rails ahead of the leading axles of the vehicle, and are so connected that voltages induced therein by control currents flowing in opposite directions in the two track rails will be additive. The receiving coils 20 and 21 are connected to the input circuit of a suitable amplifier A, this input circuit including the resistance units 22 and 23 as clearly shown in the drawings. The output circuit of the amplifier A is connected to the two windings 24 and 25 of a polyphase main car relay MR. This relay MR is of the type now common in train control practice and is provided with suitable movable contact fingers 26, 27, 28 and 29 which act to open and close suitable control circuits under different control conditions as hereinafter described.

The car-carried apparatus also includes a repeater relay RR. This relay is of the well known direct current type and is provided with two separate windings, 30 and 31. The winding 30 is arranged to be energized from a car-carried source of energy through the manually operable push button NB, the circuit for this energization of the coil 30 being obvious from the drawings. An acknowledging relay Ack is also provided on the vehicle, this relay being of the direct current two winding type. A non-control relay NC of the usual direct current type is also provided on the vehicle to maintain the vehicle carried control apparatus in its inactive condition when energized as herein-after described.

A manually operable contactor AC is provided, having a normally open contact 32 and a normally closed contact 33. The contact 33 is provided with a retarding mechanism of any suitable type which acts to prevent the opening of the circuit through the contact 33 until after the acknowledging contactor AC has been depressed for a predetermined interval of time. In the dia-

grammatic form of contactor shown, the retarding means has been illustrated as a simple dash-pot and flexible contact arrangement, designated as a whole as DP, it being understood that any other suitable timing apparatus might be used to accomplish this result. The acknowledging contactor AC is preferably located within easy access of the engineer. A second manually operable contactor RC is provided on the vehicle, having two movable contact fingers 34 and 35. This contactor is preferably located at some point on the vehicle which is not accessible while the train is in motion.

The vehicle brakes may be controlled in any suitable manner, by means of any one of a number of well known devices adapted for this purpose. As the initiation of an automatic brake application is usually accomplished by means of the de-energization of some suitable electro-magnetic device, an electro-pneumatic valve EPV has been illustrated, it being assumed that this valve acts when de-energized to impose an automatic brake application which persists until the vehicle has been brought substantially to a stop or until the vehicle speed has been reduced to a safe low limit. The electro-pneumatic valve EPV is provided with a movable contact element 36 which engages two stationary contacts 37 and 38 when the valve EPV is energized as shown, the purpose of these contacts being hereinafter explained.

One feature of the present invention comprises the provision of means for checking the operation of the car-carried receiving apparatus when no influences are being received from the trackway. This checking operation is accomplished by providing a car-carried source of energy which acts to supply control influences to the receiving coils 20 and 21, and so to energize the entire car-carried receiving circuits. This car-carried source of energy may take any suitable form of alternating current source, and in the embodiment shown, a vibratory generator or buzzer HD has been used, this buzzer comprising a primary coil 39, a vibratory armature 40 and a secondary or output coil 41. The secondary coil 41 of the buzzer HD is connected through an obvious circuit to the coils 42 and 43, these coils being mounted in inductive relation to the receiving coils 21 and 20, respectively.

Operation.—All of the circuits and devices in the drawings have been shown in their normal operating condition, that is, with a train proceeding under favorable traffic conditions in train control territory, and with all circuits and devices properly energized.

Considering first the operation of the system embodying the present invention under clear traffic conditions in a section of trackway which is equipped for automatic train

control operation, assume that the train under consideration is proceeding in the block H with no train, broken rail or other hazard affecting the flow of control current in the track 5 rails of the block I, the section J or the block K in advance. Under these conditions, train control current flows in the track rails of the block H, and induces voltages in the receiving 10 coils 20 and 21, and these voltages are amplified by the amplifier A and serve to energize the main relay MR. It should be understood that suitable condensers and reactances, included within the wholly conventionally 15 shown amplifier A, are provided in the various input and output circuits of this amplifier A, and tune the input circuits to resonance at the train control frequency, and provide a proper phase displacement between the alternating currents in the output circuits to operate 20 the main relay MR. The main relay MR is energized in its normal direction as shown, and a circuit is completed for energizing the electro-pneumatic valve EPV, which circuit may be traced as follows: from battery terminal 25 B, contact finger 26 and stationary contact for the main relay MR, wires 44 and 63, contact finger 33 and back contact of the acknowledging contactor AC, wire 45, contact finger 35 and back contact of the reset contactor RC, wires 46 and 47 and the winding 30 of the electro-pneumatic valve EPV to the battery terminal C. With the electro-pneumatic valve EPV thus energized, the vehicle under consideration may proceed in the 35 equipped territory without automatic restriction.

Considering now the operation of the system under caution traffic conditions, assume that as the vehicle approaches the entrance to 40 the block I, another vehicle is located in the section J or the block K, causing the train control current to be cut off from the track rails of the block I and placing the wayside signal at the entrance end of this block in its 45 caution position. If the engineer is alert and properly observes and recognizes the caution indication of this wayside signal at the entrance end of the block I, he depresses the acknowledging contactor AC just before the 50 vehicle enters this caution block, and thus closes a pick up circuit for the acknowledging relay Ack, which circuit may be traced as follows: from the battery terminal B, contact finger 32 and front contact of the acknowledging contactor AC, wire 48, stationary contact 55 37, movable contact 36 and stationary contact 38 of the electro-pneumatic valve EPV, wires 49 and 50 and the winding 51 of the acknowledging relay Ack to the battery 60 terminal C. The energization of the acknowledging relay Ack closes an energizing circuit for the vibrator or buzzer HD, this circuit being traceable as follows: from the battery terminal B, front contact and contact finger 52 of the acknowledging relay Ack,

wire 53, contact element 54 of the buzzer HD, vibratory armature 40 of the buzzer and the coil 39 to the battery terminal C. The energization of the buzzer HD causes an alternating current of train control frequency to flow 70 through the coils 42 and 43 of the car-carried receiving elements, in such a direction (in the present case the same in both coils) as to cause the voltages induced in the car-carried receiving coils 20 and 21 to be of such phase relation as to result in the energization of the main relay MR in the reverse direction. With the main relay MR energized reversely, a stick circuit for the acknowledging relay Ack is completed which circuit may be traced 75 as follows: from the battery terminal B, contact finger 29 and stationary contact 55 of the main relay MR, wire 56, contact finger 57 and front contact of the acknowledging relay Ack, wire 58 and winding 60 of the acknowledging relay Ack to the battery terminal C. The energization of the acknowledging relay Ack also serves to complete an alternative energizing circuit for the electro-pneumatic valve EPV, which circuit is traceable as follows: 80 from the battery terminal B, contact finger 61 and front contact of the acknowledging relay Ack, wires 62 and 63, contact finger 33 and front contact of the acknowledging contactor AC, wire 45, contact finger 35 and front contact of the reset contactor RC, wires 46 and 47 and the winding of the electro-pneumatic valve EPV to the battery terminal C. With the electro-pneumatic valve EPV thus energized and the acknowledging relay Ack maintained energized as 85 described, the vehicle may proceed through the caution block without automatic restriction. 90

If, when the vehicle approaches the exit 105 end of the caution block, traffic conditions in advance are unfavorable, that is, the next succeeding block is a caution or a danger block, the engineer is again required to operate the acknowledging contactor AC to prevent an 110 automatic brake application at this point. As the vehicle approaches the exit end of a block under unfavorable traffic conditions, the receiving coils 20 and 21 encounter the acknowledging loop 11, and the voltages induced in 115 the coils 20 and 21 by the current flowing in this acknowledging loop are enough to more than neutralize the effect of the auxiliary coils 42 and 43, to momentarily energize the main relay MR in the normal direction. 120 Whenever the main relay MR is momentarily energized normal, the stick circuit for the acknowledging relay Ack, traced above, is broken. If the engineer is alert, however, and has recognized the unfavorable signal indication and depresses the acknowledging contactor AC in recognition thereof, when first reaching a loop 11, and has so maintained it 125 until the loop is passed, the acknowledging relay Ack is maintained energized by the en- 130

ergization of its coil 51 through a circuit including the contactor AC which has been traced above. As the train under consideration passes into the next successive danger or caution block, the main relay MR is again energized in its reverse direction by means of the energy supplied from the buzzer HD, the stick circuit for the acknowledging relay Ack is again closed and the train may proceed in the caution or danger block without automatic restriction.

If the engineer is incapacitated, asleep or for any other reason fails to recognize and acknowledge an unfavorable signal indication at the entrance to a caution block, the main relay MR is de-energized after the caution block is entered. The de-energization of the main relay causes the energizing circuit for the electro-pneumatic valve EPV through the contact finger 26 to be broken, this circuit having been traced above, and an automatic brake application results, bringing the train to a stop or imposing a low speed restriction. It should be noted that the engineer may not avoid an automatic application by depressing the acknowledging contactor AC after the electro-pneumatic valve EPV has been de-energized, since the movable contact 36 of the valve EPV disengages its stationary contacts when the valve is de-energized and thus breaks the pick up circuit for the acknowledging relay Ack.

After the electro-pneumatic valve EPV has been de-energized, as a result of the failure on the part of the engineer to properly acknowledge an unfavorable signal indication, the vehicle may be released from such automatic restriction only after it has been brought to a stop. The engineer dismounts and depresses the reset contactor RC, which is located in such a position as to be accessible only from the ground, thus completing a pick-up circuit for the acknowledging relay Ack, which circuit may be traced as follows: from the battery terminal B, contact finger 29 and stationary contact 65 of the main relay MR, wire 66, contact finger 34 and back contact of the reset contactor RC, wires 67 and 50, and the winding 51 of the acknowledging relay to the battery terminal C. The energization of the acknowledging relay Ack causes the energization of the buzzer HD which supplies energy to the receiving circuits and energizes the main relay MR in its reverse direction, thus completing a stick circuit for the acknowledgment relay, including the contact finger 29 and stationary contact 55 of the main relay MR, all as described above. The vehicle may now proceed in the caution or danger block without automatic restriction, RC having been restored to its normal position.

If the engineer fails to acknowledge when passing successive danger or caution signals, the main relay MR is energized in its normal

direction by the acknowledging loop 11 at the exit end of the block as described above, and the stick circuit for the acknowledging relay Ack is broken, this circuit having been traced. The acknowledging relay Ack being de-energized, the electro-pneumatic valve EPV is de-energized as the next caution or danger block is entered, as the main relay MR is de-energized due to lack of control currents in the track rails. The buzzer HD is, of course, de-energized when the acknowledging relay Ack is de-energized.

In order that the engineer may not avoid an automatic brake application by manipulation of the manually operable contactors, the acknowledging contactor AC and the reset contactor RC are protected against misuse by means of suitable protection contacts. If the acknowledging contactor AC is secured in the depressed position in an attempt to avoid an automatic restriction, the contact finger 33 thereof disengages its front contact after a predetermined time interval, as explained above, and the energizing circuit for the electro-pneumatic valve, EPV, is broken at this point, causing an automatic brake application to be imposed. In a like manner, after the reset contactor RC is secured in its depressed position, its contact finger 35 disengages the front contact and breaks the energizing circuit to the valve, EPV, this energizing circuit through these contacts having been traced above.

It is seen from the description given that in order to avoid an automatic brake application, the engineer is forced to acknowledge each caution and danger signal. It is also seen that this acknowledging act on the part of the engineer must be performed before the block in which unfavorable traffic conditions exist is entered, and that the acknowledgement must be repeated at the entrance to successive blocks in which unfavorable traffic conditions exist.

Considering now the operation of the system in checking the receiving apparatus, assume that the vehicle under consideration has passed a caution signal, properly acknowledged, and is proceeding in a caution block without automatic restriction, and that at this time the receiving equipment fails to function by reason of a broken wire, a burned out tube in the amplifier or for any other reason. The failure of the receiving circuit will cause the immediate de-energization of the main relay MR, thus breaking the stick circuit through the contact finger 29 of this relay for the acknowledging relay Ack, and causing the de-energization of this acknowledging relay. The retraction of the contact finger 52 of the acknowledging relay Ack causes the de-energization of the buzzer HD. The retraction of the contact finger 61 of the acknowledging relay causes the de-energization of the electro-pneumatic valve EPV,

and an automatic brake application results, bringing the vehicle to a stop or substantially reducing its speed. This automatic brake application, occurring unexpectedly under unfavorable traffic conditions, apprises the engineer of the fact that the car-carried receiving apparatus is in some manner defective, and he then inspects, and if necessary, repairs, such receiving equipment before proceeding. Once the receiving apparatus has been properly repaired, the acknowledging relay Ack may be re-energized by the operation of the reset contactor RC as described above, and the train may again proceed under unfavorable traffic conditions without restriction.

Considering now the operation of the system over sections of trackway which are un-equipped for automatic train control, assume that the vehicle under consideration enters the excess energy section J from the block I , this being assumed to be the last block in an equipped section of trackway; the engineer is apprised of the fact that he is about to enter unequipped territory by means of his knowledge of the route or by means of some suitable wayside indication, and as the vehicle enters the excess energy section J he depresses the non-control push button NB , energizing the repeater relay RR through a circuit which is obvious from the drawings. The energization of the repeater relay RR causes its contact fingers 68 and $68a$ to be attracted, disengaging their back contacts and so opening normally closed shunt circuits around the resistance units 22 and 23 in the input circuit to the amplifier A , these shunt circuits being clearly shown in the drawings. The repeater relay RR is maintained energized through a stick circuit including the contact finger 27 of the main relay MR and the contact finger 69 of the relay RR , this circuit being obvious from the drawing, and for this reason the engineer need not maintain the push button NB depressed during all the time the vehicle is passing through the excess energy section J . As the control current flowing in the section J is of a far greater magnitude than that flowing in the track rails of the usual track blocks in equipped territory the insertion of the resistance units 22 and 23 in the receiving circuits does not affect the operation of the main relay MR , which relay remains energized in its normal direction as the excess energy section J is traversed. Under these conditions, a pick up circuit for the non-control relay NC is completed, which circuit may be traced as follows: from the battery terminal B , contact finger 28 and stationary contact finger 70 of the main relay MR , wire 71 , contact finger 72 and front contact of the repeater relay RR , wires 73 and 74 , and the winding of the non-control relay NC to the battery terminal C . The energization of the non-control relay NC causes its contact finger

75 to engage its front contact, thus completing an obvious energizing circuit for the buzzer HD , and supplying alternating current of train control frequency inductively to the receiving coils 20 and 21 . As the vehicle enters the first block K in non-train control territory, the main relay MR is momentarily de-energized, since the supply of current thereto, from the trackway, is discontinued, but is immediately re-energized reversely by currents induced in the receiving coils 20 and 21 from the car-carried source HD . Relay NC is designed to be slow to release so that its fingers will remain up even though it is momentarily de-energized while relay MR moves its fingers from normal to reverse position. With the main relay MR energized reversely, a stick circuit for the non-control relay NC is completed, which circuit may be traced as follows: from the battery terminal B , contact finger 28 , and stationary contact 76 of the main relay MR , wire 77 , front contact and contact finger 78 of the non-control relay NC , wires 79 and 74 , and the winding of the non-control relay NC to the battery terminal C . With the non-control relay NC energized, its contact finger 80 engages its front contact and a circuit for energizing the electro-pneumatic valve EPV is completed which circuit may be traced as follows: from the battery terminal B , contact finger 80 and front contact of the non-control relay NC , wires 81 and 47 and the winding of the electro-pneumatic valve EPV to the battery terminal C . As the train under consideration proceeds in the unequipped trackway, the receiving coils 20 and 21 are supplied with alternating current of train control frequency from the car-carried buzzer HD , the main relay MR is maintained energized in the reverse direction and the non-control relay NC is maintained energized through its stick circuit, thus maintaining the electro-pneumatic valve EPV in the energized or inactive condition and permitting the train to proceed without restriction in the un-equipped territory.

The normal control current flowing in the equipped blocks is of a magnitude sufficient to overcome the effect of HD and operate relay MR to normal position. Thus, when the train under consideration leaves the un-equipped territory and again enters a section of trackway which is equipped for train control operation, the control currents flowing in the track rails of the first equipped block, or, in case unfavorable traffic conditions exist in this block, in the acknowledging loop 11 at the exit end of this block, acts to neutralize the currents induced in the receiving coils 20 and 21 by the car-carried buzzer HD and to energize the main relay MR in its normal direction. The stick circuit for the non-control relay NC is broken when the main relay leaves its reverse energized position, the buzzer HD

- is de-energized and the alternative energized circuit for the electro-pneumatic valve EPV is broken at the contact finger 80 of the non-control relay NC. The electro-pneumatic valve EPV is, however, energized through the contact finger 26 of the main relay MR, and the train may now proceed in the equipped territory under the protection of the automatic control as described above.
- 10 If the receiving equipment should fail to operate while the train under consideration is traveling in the unequipped or non-train control territory, the main relay MR is de-energized and the stick circuit to the non-control relay NC is broken, causing the de-energization of this relay. The de-energization of the relay NC while the train is proceeding in unequipped territory causes an automatic brake application and brings the vehicle to a stop or to a safe low speed. The energizing circuit for the buzzer HD is also interrupted by the de-energization of the non-control relay NC, and the engineer is informed that the receiving equipment is out of order by the sudden brake application in unequipped territory. It should be understood that the vehicle under consideration may be provided with some suitable cut out means by which the train may be enabled to proceed either unrestricted or at some safe low speed after the failure of the receiving equipment, the engineer being informed as to the condition of the car-carried apparatus and being therefore extremely careful in his operation of the train.

When the buzzer HD is de-energized, the circuit through the secondary coil 41 thereof, and the coils 42 and 43 on the receivers, forms a closed or short-circuited secondary circuit, inductively associated with the receiving coils 20 and 21. This secondary circuit might, with some designs of receivers, act to oppose or choke the normal flux resulting from the control currents in the track rails, from the coils 20 and 21. This choking action would prevent the normal operation of the train control system, as it would produce the effect of dangerous traffic conditions in the car-carried apparatus at all times. This undesirable choking effect may be reduced to a negligible amount by so arranging the constants of the circuit including the coil 41, that very little voltage is generated in this circuit as a result of an alternating flux of train control frequency linking the coils 42 and 43. If necessary, the circuit through the coil 41 may be opened when the buzzer HD is de-energized, this being conveniently accomplished by including the front contacts of the non-control relay NC, and of the acknowledging relay Ack, in parallel in the circuit through the coil 41.

As described above, the energizing circuit for applying the train control current to the track rails at the exit end of each block in-

cludes a circuit through the corresponding acknowledging loop 11. For this reason any failure or de-energization of the acknowledging loops will cause the train control current to be cut off from the track rails of the block in which the defective acknowledging loop is located. In this manner the energization of the acknowledging loops is constantly checked, and a failure of this energization results in the automatic restriction of a train before the defective loop is encountered.

From the foregoing description it is evident that an automatic train control system has been produced in which acknowledgment of all unfavorable traffic conditions is required, in which means is provided for train operation in unequipped trackway sections, and in which the proper operation of the car-carried receiving equipment is constantly and continuously checked when no influences are being received from the trackway in unequipped or equipped trackway sections. The present invention has been disclosed in connection with a rather specific system of automatic train control, and for this reason it should be understood that many changes, modifications and additions to this system might be made without departing from the spirit of the invention as defined by the appended claims.

What is desired to be secured by Letters Patent of the United States is:—

1. In an automatic train control system, trackway means for transmitting influences to a moving vehicle under favorable traffic conditions only, a car-carried receiving circuit for receiving said influences, car-carried means for initiating a brake application when no such influences are transmitted, and apparatus for preventing said brake application provided a manual acknowledging act is performed before the cessation of said influences, said apparatus including a vehicle carried source for supplying influences to said receiving circuit.
2. In an automatic train control system, trackway means for transmitting influences to a vehicle carried receiving circuit under favorable traffic conditions only, car-carried means for initiating an automatic brake application when no such influences are transmitted, means for supplying said receiving circuit with influences from a vehicle carried source under unfavorable traffic conditions provided a manual acknowledging act is performed before the cessation of said influences from the trackway, and trackway means at spaced points, for causing said influences from said vehicle carried source to be cut off unless said manual acknowledging act is repeated at said spaced points.

3. In an automatic train control system, trackway means for continuously transmitting influences to a moving vehicle under favorable traffic conditions only, car-carried

5 electro-responsive means normally energized by said influences and adapted to initiate an automatic brake application when de-energized, a vehicle carried device, acting when energized to supply influences to said electro-
10 responsive means and thereby prevent an automatic brake application, and manually actuatable means effective to energize said device if actuated before said electro-responsive means is de-energized.

15 4. In an automatic train control system, trackway means for continuously transmitting influences to a moving vehicle under favorable traffic conditions only, a car-carried main relay normally energized through a receiving circuit by said influences, a normally energized brake applying device adapted to initiate a brake application when de-energized and maintained energized when
20 said main relay is energized, a vehicle carried influence generating device adapted when energized to supply influences to said receiving circuit and thereby to energize said main relay, and manually actuatable means, effective to cause the energization of said influence generating device if actuated while said brake applying device is energized.

25 5. In an automatic train control system, trackway means for continuously transmitting influences to a moving vehicle under favorable traffic conditions only, a receiving circuit on the vehicle for receiving said influences, a car-carried main relay energized by said influences through said receiving circuit, a normally energized brake applying device adapted to initiate an automatic brake application when de-energized and maintained energized by the energization of said main relay, and means for maintaining said main relay and said brake applying device energized while the vehicle is proceeding under unfavorable traffic conditions comprising, a vehicle carried influence generating device, acting when energized to supply influences to said receiving circuit, a stick relay for energizing said generating device when said stick relay is energized and an energizing circuit for said stick relay including a manually operable contactor and contacts closed only when said brake applying device is energized.

30 6. In an automatic train control system, trackway means for continuously transmitting influences to a moving vehicle under favorable traffic conditions only, a receiving circuit on the vehicle for receiving said influences, a car-carried three-position relay energized to assume its normal position by said influences through said receiving circuit, a normally energized brake applying device, adapted to initiate an automatic brake application, and de-energized and maintained energized by the normal energization of said three-position relay, and means for preventing an automatic brake application upon the

35 cessation of said trackway influences, comprising, a car-carried influence generating device adapted when energized to supply influences to said receiving circuit and to energize said three-position relay to assume its reverse energized position, a stick relay adapted when energized to energize said influence generating device and said brake applying device, a pick-up circuit for said stick relay including a manually operable contactor and contacts closed only when said brake applying device is energized and a stick circuit for said stick relay including a contact of said three-position relay closed only when said relay is energized to assume its reverse position.

40 7. In an automatic train control system, trackway means for continuously transmitting influences to a moving vehicle under favorable traffic conditions only, a car-carried main relay energized by said influences, a brake applying device adapted to initiate an automatic brake application when active, and maintained inactive by the energization of said main relay by said trackway means, a car-carried influence generating device adapted when energized to supply influences to said main relay, a stick relay adapted when energized to energize said influence generating device and to maintain said brake applying device inactive, a pick-up circuit for said stick relay including a manually operable contactor and contacts closed only when said brake applying device is inactive, and a stick circuit for said stick relay including contacts of said main relay closed only when said main relay is energized from said influence generating device.

45 8. In an automatic train control system for railways having portions of their trackway equipped for automatic train control and portions not so equipped, trackway means in said equipped portions for continuously transmitting influences to receiving means on a moving vehicle under favorable traffic conditions only, car-carried means for initiating a brake application when no such influences are transmitted, and apparatus for preventing said brake application providing a manual acknowledging act is performed before the cessation of said influences in said equipped portions of trackway, or before the vehicle enters said unequipped portions of trackway, said apparatus including a vehicle carried device for supplying influences to said receiving means.

50 9. In an automatic train control system for railways having portions of their trackway equipped for automatic train control and portions not so equipped, trackway means in said equipped portions for continuously transmitting influences to a moving vehicle under favorable traffic conditions only, trackway means at the entrance to said unequipped portions for transmitting distinc-

tive influences to the vehicle, a car-carried main relay energized by said trackway influences through a receiving circuit, a normally energized brake applying device acting to initiate an automatic brake application when de-energized and maintained energized when said main relay is energized by said trackway influences, a car-carried influence generating device adapted when energized to supply influences to said main relay through said receiving circuit, an acknowledging stick relay acting when energized to energize said influence generating device and said brake applying device, a pick-up circuit 10 for said acknowledging relay including a manually operable contactor and contacts closed only when said brake applying device is energized, a stick circuit for said acknowledging relay closed only when said main relay is energized by said influences from said car-carried generating device, a non-control stick relay, acting when energized to energize said influence generating device and said brake applying device, a pick-up circuit 20 for said non-control relay closed only if a manually operable contactor is operated when said trackway means at the entrance to said unequipped portions of trackway is encountered, and a stick circuit for said non-control relay closed only when said main relay is energized by influences from said car-carried generating device.

10. In an automatic train control system for railways having portions of their trackway equipped for automatic train control and portions not so equipped, trackway means in said equipped portions for continuously transmitting influences to receiving means on a moving vehicle under favorable traffic conditions only, a car-carried brake applying device adapted to initiate an automatic brake application when active, car-carried control means for maintaining said brake applying device inactive so long as said influences are received from the trackway, means including a car-carried influence generating device to at times affect said receiving means for maintaining said brake applying device inactive when the vehicle is traveling under unfavorable traffic conditions in said equipped portions of trackway, and further means, also including said car-carried influence generating device, for maintaining said brake applying device inactive when the vehicle is traveling in said unequipped portions of trackway.

11. In an automatic train control system for railways having portions of their trackway equipped for automatic train control and portions not so equipped, trackway means in said unequipped portions for continuously transmitting influences to a moving vehicle under favorable traffic conditions only, trackway means at the entrance to said unequipped portions of trackway for transmitting a distinctive influence, different from the influence

transmitted at any other portion of trackway to the vehicle, a car-carried brake applying device adapted to initiate an automatic brake application when active, car-carried control means for maintaining said brake applying device inactive so long as said influences are received from the trackway, a car-carried influence generating device, means including said generating device and a manually energizable relay acting to maintain said brake applying device inactive when the vehicle is traveling under unfavorable traffic conditions in said unequipped portions of trackway provided said relay is manually energized before said unfavorable traffic conditions are encountered, and means including said generating device and a second manually energizable relay, acting to maintain said brake applying device inactive while the vehicle is traveling in said unequipped portions of trackway, provided said second manually energizable relay is energized while said distinctive influence is being transmitted to the vehicle.

12. In an automatic train control system, trackway means for transmitting influences to a receiving circuit on a moving vehicle only under favorable traffic conditions, car-carried means for initiating a restriction on the car when no such influences are transmitted, and apparatus, including a car-carried source of energy, for preventing such a restriction by energizing said receiving circuit.

13. In an automatic train control system, trackway means for transmitting influences to a circuit on a moving vehicle only under favorable traffic conditions, car-carried means for initiating a restriction on the car when no such influences are transmitted, and apparatus which, only when operated, substitutes, for said influences, other influences of a distinctive character to said circuit, to thus prevent said restriction.

14. In an automatic train control system, trackway means for transmitting electrical influences to a moving vehicle only under favorable traffic conditions, car-carried means for initiating a restriction on the car when no such influences are transmitted, and manually operable apparatus, for replacing said influences by other influences of a distinctive character from said influences, for preventing said restriction in the same manner as did said electrical influences.

15. In an automatic train control system, trackway means for transmitting influences to a receiving circuit on a moving vehicle only under favorable traffic conditions, car-carried means for initiating a restriction on the car when no such influences are transmitted, and apparatus operable for substituting, for said influences, other influences from a car-carried source of energy, to affect said receiving circuit, which other influences per-

sist after completion of the operation of said apparatus, to thus prevent said restriction.

16. In a train control system, a car-carried means including receiving means automatically responsive to traffic conditions in train control territory, a train restricting device controlled by the responsive means to cause a train restriction, and apparatus including a car-carried source of energy, at times applicable to said receiving means, operable to prevent a train restriction by causing an energization of the receiving means different from what occurs in train control territory and which persists after the completion of the operation of said apparatus.

17. In a train control system, a car-carried relay responsive in train control territory to assume different positions in accordance with traffic conditions, a train restricting device controlled by said relay to at once cause a train restriction, a car-carried source of energy, and car-carried apparatus operable to prevent such a train restriction by energizing said relay from said car-carried source so as to assume a position which is different from any caused by traffic conditions.

18. In an automatic train control system, trackway means for continuously transmitting influences to a moving vehicle under favorable traffic conditions only, car-carried electro-responsive means normally energized by said influences and adapted to initiate an automatic brake application when deenergized, a vehicle carried device, acting when energized to supply influences to said electro-responsive means and thereby prevent an automatic brake application, and manually actuatable means effective to energize said device.

In testimony whereof I affix my signature.

WADE H. REICHARD.
